CAP HANDLING MACHINE

Fowler E. Macy, Converse, Ind.

Application August 13, 1934, Serial No. 739,711

10 Claims. (Cl. 198—33)

This invention relates to a machine for handling paper caps such as used in connection with milk bottles and more especially caps having two diametrically opposed tabs.

5 After the caps have been cut difficulty has been experienced in properly positioning them so that the corresponding tabs on all of the caps will be properly aligned.

The present invention provides a means where-
10 by caps of the type mentioned can be properly positioned for packaging or for admission to a capping mechanism.

Another object is to provide a machine of this character which is simple and durable in
15 construction and will operate rapidly and efficiently to produce the desired results.

With the foregoing and other objects in view which will appear as the description proceeds, the invention consists of certain novel details of
20 construction and combinations of parts herein-
after more fully described and pointed out in the claims, it being understood that changes may be made in the construction and arrangement of parts without departing from the spirit of the
25 invention as claimed.

In the accompanying drawings the preferred form of the invention has been shown.

In said drawings

Figure 1 is a plan view of the machine.

30 Figure 2 is an end elevation, the drive shaft being shown in section.

Figure 3 is an enlarged section on line 3—3, Figure 1, caps being shown by broken lines in several positions on the feeding screws.

35 Figure 4 is a section on line 4—4, Figure 1.

Figure 5 is an enlarged section on line 5—5, Figure 1.

Referring to the figures by characters of reference, 1 designates a rigid frame one end of
40 which is formed of spaced cross members 2 and 3. At intermediate points the sides are connected by cross strips 4 and at the other end there are arms 5 extending from the sides and joined by a strip 6.

45 Bearing in the cross members 2 and 3 are shafts 7 and 8 arranged in pairs, and secured to and rotatable with each of the shafts is a screw 9. The shafts of each pair are adapted to rotate simultaneously in opposite directions respectively
50 and the threads of the screws are so pitched that, during this rotation, any articles engaged thereby will be fed longitudinally of the shafts.

By referring to Figure 1 it will be noted that the threads on one screw of each pair fit between
55 the threads of a screw of the next adjoining pair

and in order that all of the screws may be rotated in the proper directions a train of gears 10 is carried by the several shafts. One of the shafts 7 is adapted to receive motion through gears 11 from a shaft 12 driven by any suitable power.

Those portions of the cross member 3 between the shafts 7 and 8 are cut away or recessed as shown at 13 and extending from this member 3 are pairs of oppositely disposed guide strips 14 which are transversely concave. These strips are 10 spaced apart at their lower edges to provide a slot 15 and the two strips of each pair cooperate to form a guide channel extending from member 3 to the remote end of the machine and which channel is free of all obstructions.

In order that the strips 4 and 6 may offer no obstruction to the movement of tabs depending through and slideable along the slots 15, these strips are cut away under the slots as shown at 16 in Figure 5. The strips 14 are rigidly held 20 by the strips 4 and 6 and the bottom portions of these strips are cut away adjacent to the member 3 so as to provide an enlargement of each slot 15. This enlargement has been indicated at 17 in Figure 1.

Extending from the member 2 below the space between the screws of each pair is a supporting rod 18 which projects through the recess or cut away portion 13 and into the enlarged portion 17 of the adjacent slot 15. Another rod 19 is arranged at one side of the rod 18 and also extends through the adjacent recess 13 and into the enlarged portion 17 of the slot. Rod 19 has its end portions parallel with rod 18 while an intermediate portion is offset obliquely as shown. Thus 35 the free end portions of the rods 18 and 19 are closer together than the remaining portions and the space between them is adapted to substantially align with the adjacent slot 15.

A reciprocating bar 20 is carried by the sides of frame 1 and is adapted to be actuated rapidly by any suitable means such as a ratchet wheel 21 a portion of which has been indicated in Figure 1.

To this bar are rigidly connected spaced pairs of fingers 22 located under the bottom edges of the strips 14 and having their upper ends diverging from each other and secured to arcuate jarring plates 23. These plates bear against the outer surfaces of the strips 14. Pins 24 are extended upwardly from bar 21 near the sides of frame 1 and springs 25 serve to connect these pins to those plates 23 nearest the sides of frame 1. Interposed between the remaining plates are springs 26 joined thereto in any suitable manner.

Secured to the member 3 are guide fingers 27

which extend laterally to points above one side of the recesses 13 and thence rearwardly over the adjacent screws 9.

By referring particularly to Figure 3 it will be noted that one screw 9 of each pair has a portion of its hub cut away at 28. This is for the purpose hereinafter explained.

The caps C having oppositely extending tabs c are adapted to be delivered promiscuously upon the screws 9 which are in constant rotation, one screw of each pair turning oppositely to the other screw of the same pair. If one of the tabs is lowermost when the cap is deposited on the screws it will drop downwardly between the rods 18 and 19 and the two screws, by engaging opposed portions of the cap will feed the cap longitudinally along these rods. As the rods converge toward the guide channels they will act to bring succeeding tabs into proper alignment so as to enter slot 15 as the caps are received in the channels formed by the strips 14.

Should a cap fall onto the screws in such a manner as to cause one of its tabs to engage the guide finger 27 as at the right in Figure 3, the other tab would be supported by the hub of the adjacent screw. Thus the cap would be held elevated while being fed forwardly by the screws until the right hand tab c at the right of Figure 3 is brought to position where the hub is cut away as at 28. At that time the rotating hub will ultimately provide sufficient clearance to enable the tab to swing downwardly past the hub sufficiently to the lower position shown by broken lines at the right of Figure 3. After reaching this position the cap will travel along the screws until its lower tab ultimately slips off of its supporting rod 18 so as to be properly guided into the adjacent slot 15.

If by any chance a cap should fall onto the screws with both of its tabs resting on the hubs of the screws, as shown by broken lines at the left of Figure 3, said cap will ultimately be released and guided in the same manner as heretofore described.

45. The rapidly reciprocating bar 21 sets up a light jarring action upon the strips 14 through plates 23 and fingers 16 and this action will be sufficient to prevent the caps from becoming hung within the guide channels and allow them to be fed easily 50 along said channels until delivered at their remote ends.

What is claimed is:

1. A machine for handling bottle caps having separate tabs including spaced feeding screws, 55 means for rotating the screws in opposite directions respectively, a guide channel for receiving caps delivered thereto by the screws, there being a longitudinal slot in the bottom of the channel for the reception of a depending tab on a supported cap, and means adjacent to the screws for positioning screw engaged caps with one tab below the other.

60. A machine for handling bottle caps having separate tabs including spaced feeding screws, 65 means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below 70 the other, and means for guiding the lowermost tab into the slot in the guide channel during the movement of the cap into the channel under the action of the feed screws.

3. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, means for guiding the lowermost tab into the slot in the guide channel during the movement of the cap into the channel under the action of the feed screws, there being a recess in one of the screws for releasing a tab if supported on the screws. 15

4. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, means for guiding the lowermost tab 20 into the slot in the guide channel during the movement of the cap into the channel under the action of the feed screws, there being a recess in one of the screws for releasing a tab if supported on the screws, and means for intermittently jar- 25 ring the channel guide.

5. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, means for guiding the lowermost tab 30 into the slot in the guide channel during the movement of the cap into the channel under the action of the feed screws, there being a recess in one of the screws for releasing a tab if supported on the screws, and means for intermittently jar- 35 ring the channel guide.

6. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, and means for jarring the guide channel 40 intermittently.

65. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, and means for jarring the guide channel 70 intermittently.

70. A machine for handling bottle caps having separate tabs including spaced feeding screws, means for rotating the screws in opposite directions respectively, a guide channel for receiving caps delivered thereto by the screws, there being a longitudinal slot in the bottom of the channel for the reception of a depending tab on a supported cap, means adjacent to the screws for positioning screw engaged caps with one tab below the other, means for jarring the guide channel intermittently, said means including a bar mounted for reciprocation, jarring elements contacting with the walls of the channel guide, and 75

resilient connections between said members and the bar.

8. The combination with a channel guide having a longitudinal slot in the bottom thereof for receiving the lowermost tab of a cap having separate tabs, said walls being enlarged at one end, of converging supporting rods extending into the enlargement for guiding the lowermost tab of a cap into the slot, spaced feed screws above the rods rotatable in opposite directions respectively, and a guide finger overlying and extending longitudinally of one of the screws.

15 9. The combination with a channel guide having a longitudinal slot in the bottom thereof for receiving the lowermost tab of a cap having separate tabs, said walls being enlarged at one end, of converging supporting rods extending into the

enlargement for guiding the lowermost tab of a cap into the slot, spaced feed screws above the rods rotatable in opposite directions respectively, one of the screws having a hub with a cut away portion for the release of a tab if supported by the hub.

10. In a machine of the class described a channel guide having a longitudinal slot, feed screws for engagement by a plurality of caps each with separate tabs, said screws cooperating to direct the caps successively into the channel guide, and means cooperating with the screws for positioning the caps each with one of its tabs extending downwardly for movement into the slot.
